CLAIM

The ornamental design for a case for an electronic communications device, as shown and described.

DESCRIPTION

FIG. 1 is a front perspective view of a case for an electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detail view of the encircled portion in FIG. 2.

The dashed broken line in FIG. 1 forms no part of the claimed design. Except for the interior regions immediately surrounding the openings and buttons that are bounded by solid lines, the interior surfaces of the case shown in FIGS. 1–3 also form no part of the claimed design. The dot-dash broken line circle in FIG. 2 delineates a portion of the case for an electronic communications device that is part of the claimed design and is shown on an enlarged scale in FIG. 9.
